UNITED STATES PATENT OFFICE.

CHARLES B. McDONALD AND WALTER WAGNER, OF CHICAGO, ILLINOIS.

CAN-SOLDERING MACHINE.

SPECIFICATION forming part of Letters Patent No. 391,171, dated October 16, 1888.

Application filed May 21, 1888. Serial No. 274,473. (No model.)

To all whom it may concern:

Be it known that we, CHARLES B. McDONALD, a citizen of the United States, and WALTER WAGNER, a citizen of Switzerland, residing at Chicago, in the county of Cook and State of Illinois, have invented certain new and useful Improvements in Can-Soldering Machines, which are fully set forth in the following specification, reference being had to the accompanying drawings, forming a part hereof, and in which—

Figure 1 shows our improved can soldering machine in side elevation, as seen from the front or working side thereof. Fig. 2 shows on an enlarged scale, on the line $x-x$ of Fig. 1, a transverse view through the soldering-pots and the positions of a can in each soldering-pot. Fig. 3 shows a transverse view of the machine on a plane, $y-y$, of Fig. 1, the position 15 of the can-carrier with its chucks open in the lower and closed in the upper position, and the end of the chuck-spindle i in its groove m . Fig. 4 shows an enlarged view of a link and its can-carrier in vertical end elevation, taken on the plane $x-x$ of Fig. 6, as seen from the forward end of said Fig. 6. Fig. 5 is a rear view 20 of an entire chain-link and its rollers, with a can-carrier and its lever and springs. Fig. 6 shows in plan an entire chain-link and its attached rollers and all that part of the can-carrier below the plane $y-y$ of Fig. 4. Fig. 7 shows the lever i' and its attached parts in plan view.

Like letters of reference refer to like parts. 25 The object of our invention is to construct a can-soldering machine in which both ends of the can are soldered to the can-body by a single insertion of can into the machine, and to prevent the solder from flowing to one side or lumping by causing the can to assume a vertical position immediately after being soldered; and to attain said ends we construct our improved can-soldering machine substantially as follows, namely:

40 We mount an endless chain or belt, a , upon two drums or wheels, b b' , which preferably, and as here shown, run in a vertical plane. The shafts of said wheels are carried on bars c , which connect two upright standards, d , at 45 each end of the machine. A similar standard is placed in the middle of the machine and is connected to said end standards by means of

connecting-bars. Upon one side of the chain each link has a pair of lugs or arms, e , between which and on pins f is hinged a can carrier, g , 55 which is free to revolve in a plane around and at right angles to the axes of the pins f , which enter into the ends of the short shaft g' , forming a part of the can-carrier g . Each chain-link has at one end a pair of lugs or arms, a^2 , 60 and at its opposite end a single central lug, a^3 , which passes between the two lugs a^2 of the next preceding or succeeding link, as plainly shown in Fig. 6, and which are there connected by means of a pin, a^3 , passing through said 65 lugs, so as to permit said joint to work freely when the chain is passing around said drums, and on each of the ends of said pin or pins a^3 , outside of the lugs a^2 , are mounted rollers a^4 a^5 , the former a plain drum and the latter provided with a flange at both its ends. 70

Each joint of the endless chain is made and provided with rollers, as just described, and is carried upon tracks or chain-carriers a^6 a^7 , attached to the standards d . Said tracks a^6 a^7 75 are placed, respectively, above and beneath the rollers a^4 a^5 , to guide and keep the links of the chain moving in a true line.

The weight of the can-carrier g and its load tends to twist each link of the chain from a 80 horizontal toward a vertical plane around the pulley a^5 , and therefore the track a^6 is above the roller a^4 and the track a^7 under the roller a^5 . The flanges on each side of the rollers a^5 will cause them and all attached parts to move 85 in a true vertical plane with the track a^7 . There is also a hood or semicircular covering, b^2 , around the outer half of the wheels b b' to hold the links and their pulleys a^4 a^5 in place while they pass from the tracks over and 90 around the outer halves of said drums.

The tendency of the can-carrier g is to fall into a horizontal position at right angles to that shown in Fig. 3 as it hangs and turns freely on the pins f ; but the desired normal 95 position of the axis of the cans is vertical to the chain-carriers or tracks or the chain on said tracks. Therefore, in order to keep the carrier vertical or inclined at such times and places as desired, suitable cams, tracks, and guides are employed, as hereinafter shown.

The opening or receiving end of the machine is from the points h to h' h^2 , the points h h' h^2 indicating a cam which serves to open the

chucks to discharge the finished can, and also at the proper time to close the chucks *i* upon the can ends. The said cam *h* *h* *h*² begins at about the center of the shaft of the wheel *b*, or at about the point where the flat straight cam *J* terminates, which point may be at any place convenient above the shaft, as here shown, and at any convenient point, as at about an angle of forty-five degrees from the vertical of the axis of the wheel-shaft. The cam has a short rise, *h*', at the outer end of which it forms an approximately continuous circle from the center until it comes to a point vertically below the center of the wheel-shaft, after which it continues its surface as a tangent to said circle until it reaches the point *h*', where it gradually rounds off upward at about the relative distance from the wheel-shaft, as shown in Fig. 1, or at a point which is back far enough to permit the chucks *i* to close upon the can ends before the lower roller, *i*^x, on the cam *j*' gets to the receding curve *j*², which forms a part of the cam *j*'. The chucks *i* are opened by means of said cam at the point *h*', which there depresses the roller *i*^x and spring *i*^y, thus separating the chucks *i*, where they discharge the cans from the machine and where they may fall into any suitable conductor or hopper and through it be led off to any suitable receptacle.

After the chucks *i* reach the position vertically under the tangent part of said cam they are horizontal and ready to receive cans which are there fed into the machine as they pass along under said cam, which is made long, so as to allow plenty of time to feed the cans into it.

Upon each of the shafts of the wheels *b* and *b*' is mounted a semicircular guide, *m*, in which the wheel-shaft turns. Said cam is held in place by means of a hub which reaches back to and is attached to the hub of the cam *h* *h*², also mounted loosely on the same shaft in the same manner and held from turning by means of a connecting-bar, *h*³, connected to some part of the frame, as to the cam or bar *j*, (shown in Fig. 1,) or by means of a bar, *h*⁴, connected to the frame *d*, or by any similar device.

At about the middle of the receding part of the cam *j*—that is, in the middle of the cam *j*²—begins the lower solder-trough, *k*, which is made long enough to permit each can to make several complete revolutions in it from the time it dips into until it leaves its fluid solder. Said trough *k* is held on brackets *k*² and arranged so that the surface of the solder may be nicely adjusted to the can. In this case the bed-plate *k*⁴ of the trough *k* is shown held by a screw-bolt, *k*³, through the bracket *k*², and when necessary wedges (not shown) may be driven under the bed-plate to adjust the trough *k*, and on said bracket, or attached to the frame of the machine, is held a cam, *j*³, both ends of which have cams bent so as to be about parallel to the ends *j*² of the cams *j*', which they overlap. Said cam *j*³, as also the cam *j*⁴, is so placed as to cause the upper roller, *i*^x, to fall upon it when the can-carrier *g* is

released from the lower cam, *j*' *j*². Said roller by its friction causes its can to revolve, as shown by the arrows, with the motion of the chain, so as to give the edge dipping into the solder sufficient time to become thoroughly soldered during the time that the can is passing through said soldering-trough.

At the farther end of the solder-pot *k* the cam *j*³ is formed just as it is at the near end, and thereby as the can advances it again rises toward the perpendicular, and there the lower roller, *i*, is caught by a receding portion, *j*², on a cam, *j*', made in every way in this respect as the cam *j*' at the front of the soldering-pot, except that it points in the opposite direction, from which it is again raised and held in the perpendicular position, and through this construction the can is again caused to revolve in the opposite direction, as shown by the arrows.

After the lower ends of the cans have been thus completed they pass on and over the wheel *b*', and thus become inverted, where by an arrangement of cams *j*', constructed, placed, and operating precisely as said parts already described in passing the cans through the trough *k*, the now lower edges of the cans pass into and through the trough *k*' and are turned on the spindles *i*', in the direction indicated by the arrows, by means of the cam *j*⁴, which is constructed and arranged precisely as the cam *j*³, the cans becoming through it erected as they leave the solder pot or trough *k*'. The cans are received and held on a cam, *j*', and passed along to the discharging end of the machine through mechanism constructed and operating as already described.

The opposed revolving plates or chucks, *i*, are carried on spindles *i*' in the same axial line, provided with rollers *i*^x, so placed as to leave a free outer end, *i*', which passes into the groove *m*' in the semicircular guide *m* at the tangential point, when the roller *i*^x begins to leave the straight cams *j*' *j*² and passes around the wheels *b* *b*', by means of which the cans are held erect and guided in their passage from the lower to the upper cams, and vice versa.

On the spindle or spindles *i*', which are uppermost when on the lower side of the machine, there is secured a grooved collar, *i*³, in the groove of which enter the points of pins *i*⁴, passed through the opposite ends of the forked lever *a*⁴. Said arrangement permits a free revolution of the spindle *i*', while at the same time the chucks *i* may be separated by means of said lever, which is fulcrumed at *i*⁵ to the can-carrier *g*.

The chucks *i* are held closed upon the can by means of spiral springs *i*⁵, of which the upper ends bear against lugs *i*⁶ of the lever *i*⁴ and their lower ends rest upon lugs *i*⁷, forming a part of the can-carrier *g*. The rod *i*⁸, passing through the coiled springs *i*⁷, also rests on the lugs *i*⁶ and pass freely through *i*⁷ on the lever *i*⁴.

The wheels *b* *b*' have sprockets *b*², which fit into the links *a*, and thereby secure uniform and positive motion to all the parts.

The mechanism may be actuated from the shaft of either of said wheels, to which suitable power may be applied. One method of doing this is illustrated in Fig. 3, where a pulley, 5 b^4 , is attached to one of said drum-shafts and is driven by a belt, b^5 , from a cone-pulley, as shown, and of well known construction. The said cone-pulley has a pinion, n , securely attached to it, which operates a gear-wheel, n' , 10 turning loosely on a stud attached to the frame of the machine, and attached to said wheel n' and turning with it is a pinion, n^2 , which drives a wheel, n^4 , which runs loosely on the hub of the said cone-pulley o , and has attached 15 to it a belt or chain pulley, n^5 , from which the belt b^5 drives the pulley b^4 , which turns the shaft and drum b , which gives the desired motion to the endless chain a . Each of said wheels b b' is also provided with a groove 20 which receives the inner flange of the rollers a^5 as it passes around them.

The advantages obtained in the herein described and claimed construction are these, namely: There being but a single insertion or 25 handling of the can to solder both ends, there is but half the liability to imperfect chucking that there is where the cans have to be taken out, inverted, and rechucked. There is, therefore, less than half the manual labor, and, 30 second, when a can end has passed through the solder bath it is liable to have lumps of solder, &c., on it, which will prevent proper chucking, and thereby cause the can to wobble, and such motion will cause imperfect 35 soldering of the other joint, and, finally, when a can has been soldered and is then held in a position with its axis either inclined or parallel to the plane of the horizon, the solder before cooling is sure to flow more or less upon 40 the under side of the can and cause an unsightly excess and a weakening of the upper part of the joint, all of which we consider serious objections and which we overcome perfectly in our construction.

45 What we claim is—

1. In a can soldering machine adapted to automatically invert and solder both ends of the can in a single passage through it, a soldering device, an endless chain moving in a 50 vertical plane over revolving drums and horizontal chain-tracks, said chain provided with hinged laterally-oscillating can-carriers adapted to carry the axis of the cans parallel to the plane of motion of said chain, said can-carriers actuated by fixed cams, and guides to hold the can-carriers when moving around the drums from one set of cams to the other, substantially as specified.

2. In a can-soldering machine, a soldering 60 device, a hinge-jointed endless chain moving in a vertical plane over revolving drums and straight chain-tracks, said chain provided with hinged laterally-oscillating can-carriers, wherein the normal position of the axis of the 65 cans is vertical to said chain-tracks and parallel to the plane of motion of said chain, stationary cams to oscillate said can-carriers, and

guides to guide said can-carriers around the revolving drums, substantially as set forth.

3. In a can-soldering machine, an endless 7 chain moving in a vertical plane over revolving drums and upper and lower straight chain-tracks, said chain provided with laterally-oscillating can carriers, wherein the normal position of the axis of the cans is vertical to said 75 chain-tracks and parallel to the plane of motion of said chain, stationary cams to oscillate said can carriers, with fixed guides to guide them from can to can around said drums, and a soldering device under both the lower and 80 upper horizontal parts of said chain, whereby alternately the opposite can ends are soldered, substantially as specified.

4. In a can-soldering machine, an endless 85 chain moving in a vertical plane over revolving drums and fixed chain-tracks, laterally-oscillating can-carriers which carry the axes 90 of the cans parallel to the plane of motion of the chain, attached to said chain and provided with revolving and spindled end 95 chucks closed by a spring-actuated lever attached to said can-carriers and opened by a cam operating on said lever, fixed cams to give lateral oscillation to said can-carriers and to revolve said chucks, and a solder bath, substantially as specified.

5. In a can-soldering machine, soldering devices and an endless chain moving in a vertical plane over fixed straight chain-tracks and revolving drums, laterally-oscillating can-carriers which carry the axes of the cans parallel 100 to the plane of motion of the chain, provided with revolving and spindled end chucks attached to said chain, and rollers attached to said chucks, and fixed cams on opposite sides 105 of the plane of motion to oscillate said can-carriers and to revolve said chucks in alternately-opposite directions, substantially as specified.

6. In a can-soldering machine, horizontal 110 chain-tracks, an endless chain moving in a vertical plane provided with hinged laterally-oscillating can-carriers wherein the normal position of the axis of the cans is vertical to said 115 chain-tracks and parallel to the plane of motion of said chain, whereby the cans, with said carriers, through said motion become vertically reversed end for end, stationary cams to oscillate said can-carriers, and guides to hold 120 said can-carriers while moving from one cam to the other, and a soldering device under the horizontal parts of said chain, substantially as specified.

7. In a can-soldering machine, an endless 125 chain having flat links provided with hinged joints moving over revolving drums, said chain-links provided with track-rollers on their opposite edges which run on tracks, whereof the rail nearest the carrier is under the roller and the opposite rail is over the opposite roller, a solder bath, and hinged laterally-oscillating 130 can-carriers actuated by fixed cams, substantially as specified.

8. In a can-soldering machine, a soldering device, an endless chain having flat links pro-

vided on its edges with flanged rollers and hinged can-carriers, in combination with a track consisting of a pair of rails, of which the rail nearest the can carrier is below and the 5 opposite rail above the said rollers, substantially as specified.

9. In a can-soldering machine, horizontal chain-tracks, an endless chain moving in a vertical plane provided with hinged laterally-oscillating can-carriers, wherein the normal position of the axis of the can is vertical to said chain-tracks and parallel to the plane of motion of said chain, whereby the cans, with said carriers, through said motion become vertically 10 reversed end for end, stationary cams to oscillate said can-carriers provided with revolving chucks having rollers on their chuck-spindles, and cams to rotate said chucks, and a solder- 15

ing device under said chain tracks, substantially as specified. 20

10. In a can-soldering machine, a soldering device, horizontal chain-tracks, an endless chain moving in a vertical plane over revolving drums and on said tracks, and laterally-oscillating and inverting can-carriers provided with horizontally - revolving and automatically opening and closing chucks, said chucks being closed by a spring-actuated lever and re- 25 volved and opened, and said carriers oscillated by fixed cams, substantially as specified.
